CLAIM

The ornamental design for a display screen with graphical user interface as shown and described.

DESCRIPTION

FIG. 1 is a front view of a first embodiment of a display screen with graphical user interface;

FIG. 2 is a first front detail view of a portion of the first embodiment of the display screen with graphical user interface;

FIG. 3 is a second front detail view of a portion of the first embodiment of the display screen with graphical user interface;

FIG. 4 is a front view of a second embodiment of a display screen with graphical user interface;

FIG. 5 is a first front detail view of a portion of the second embodiment of the display screen with graphical user interface;

FIG. 6 is a second front detail view of a portion of the second embodiment of the display screen with graphical user interface;

FIG. 7 is a front view of a third embodiment of a display screen with graphical user interface;

FIG. 8 is a first front detail view of a portion of the third embodiment of the display screen with graphical user interface; and,

FIG. 9 is a second front detail view of a portion of the third embodiment of the display screen with graphical user interface.

In the drawings, the dot-dash broken lines indicate where enlargements have been taken only and form no part of the claim, and all other broken lines depict environmental subject matter only and form no part of the claim.
